The ornamental design for an excavator bucket, as shown and described.

DESCRIPTION

FIG. 1 is a front and right side perspective view of a first embodiment of an excavator bucket showing my new design;

FIG. 2 is a rear and left side perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side elevation view thereof;

FIG. 8 is a right side elevation view thereof;

FIG. 9 is a front and right side perspective view of a second embodiment of an excavator bucket showing my new design;

FIG. 10 is a rear and left side perspective view thereof;

FIG. 11 is a top plan view thereof;

FIG. 12 is a bottom plan view thereof;

FIG. 13 is a front elevation view thereof;

FIG. 14 is a rear elevation view thereof;

FIG. 15 is a left side elevation view thereof; and,

FIG. 16 is a right side elevation view thereof.
